REFLECTOR

Sidney A. Heenan, Park Ridge, Ill., assignor to Amerace Esna Corporation, Union, N.J.

Filed Nov. 5, 1969, Ser. No. 20,076

Term of patent 14 years

Int. Cl. D29—99

U.S. Cl. D72—1

FIG. 1

FIG. 4

FIG. 3

FIG. 2

FIG. 5

FIG. 6

FIG. 1 is a front elevational view of a reflector incorporating my new design;

FIG. 2 is a greatly enlarged fragmentary front view of the portion of the reflector of FIG. 1 in the circle 2;

FIG. 3 is a view in vertical section taken along the line 3-3 of FIG. 2;

FIG. 4 is a view in vertical section taken along the line 4-4 of FIG. 1, on the same scale as FIG. 3;

FIG. 5 is a front elevational view of a reflector incorporating another embodiment of my new design; and

FIG. 6 is an enlarged fragmentary rear view of the portion of the reflector of FIG. 1 in the circle 2, on one half of the scale of FIG. 2.

I claim:

The ornamental design for a reflector, as shown and described.
